(57) **CLAIM**

I claim the ornamental design for a personal aircraft, as shown and described.

DESCRIPTION

FIG. 1 is a perspective view of a personal aircraft, as viewed from the top and rear.

FIG. 2 is a perspective view of the personal aircraft of FIG. 1, as viewed from the top and front.

FIG. 3 is a side view of the personal aircraft of FIG. 1, the opposite side being a mirror imager thereof.

FIG. 4 is a front elevation view of the personal aircraft of FIG. 1.

FIG. 5 is a top plan view of the personal aircraft of FIG. 1.

FIG. 6 is a rear elevation view of the personal aircraft of FIG. 1; and,

FIG. 7 is a bottom plan view of the personal aircraft of FIG. 1. The dashed lines in the drawings are for illustrative purposes and form no part of the claimed design.
